GUSSETED PLASTIC HANDBAG

Janet Samuelson, Lehighton, Pa.

Application October 31, 1944, Serial No. 561,237

9 Claims. (Cl. 150—28)

This invention relates to handbags having walls characterized by a multiplicity of decorative plastic elements.

Heretofore such handbags have been made with the decorative plastic elements strung on tapes at the side and end walls of the bags. These bags have therefore been without the flexible end gussets which add so much to utility and convenience that they were practically always used before the advent of these plastic handbags. The reasons for the omission of the gussets in plastic handbags were that they clashed in appearance with the rest of the handbag and that they did not lend themselves to reliable and inexpensive fabrication with the bottom and side walls of the handbag.

It is therefore an object of the invention to provide a plastic handbag having improved means including gussets or whereby gussets are reliably and cheaply connected to the bottom and side walls of the bag.

Another object of the invention is the provision of a handbag having end gussets and improved plastic decorative portions partly overlying the gussets without interfering with their freedom of movement.

I have found that the cheapest and best way of connecting gussets of pliable material to the plastic side walls is to thread the horizontal lacing of the plastic decorative elements through holes cut in the edge portions of the gussets. But these unfinished holes eventually become ragged and it would be too expensive to finish them off with eyelets or by sewing. I have accordingly conceived the idea of utilizing portions of adjacent decorative plastic elements for the dual purpose of concealing the holes in the gussets and of affording plastic ornamentation at least partly overlying the gussets.

Another object of the invention, therefore, is to provide improved means comprising a perforated gusset secured by the lacing of the plastic decorative elements, the latter having portions overlying the perforations.

Another object of the invention is the provision of a handbag having improved means whereby the lacing referred to is also threaded through the overlying plastic portions to more securely anchor the gusset in the adjacent corners of the bag and to facilitate the threading.

Another object of the invention is to provide improved means whereby certain of the plastic elements have reinforced extensions at the gusset, which extensions may be adapted to protect the adjacent lacing.

Another object of the invention is to provide improved means whereby extensions of plastic elements are operative to prevent the gussets from being pushed outward by the contents of the bag.

Another object of the invention is to furnish improved means such that the extensions of certain of the plastic decorative elements at the end gussets shall not interfere with the flexing or bulging of the side wall under the pressure of the contents of the handbag.

Another object of the invention is to furnish improved plastic decorative elements having extensions as set forth and being adapted to be inexpensively molded.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in side elevation showing a handbag embodying the invention.

Fig. 2 is a view in end elevation thereof.

Fig. 3 is a similar view but showing the handbag in closed position.

Fig. 4 is an enlarged end view like that of Fig. 2 but with parts broken away.

Fig. 5 is an enlarged fragmentary sectional view taken on line 5—5 of Fig. 4.

Fig. 6 is a rear plan view of a decorative plastic element according to the invention, with lacing tapes shown in dot-dash lines.

Fig. 7 is a view in end elevation showing a modification of the invention, with parts broken away along the dot-dash line.

Fig. 8 is a section on line 8—8 of Fig. 7.

Fig. 9 is a rear plan view of a plastic decorative element according to the modification.

Fig. 10 is an edge view of another modification of a plastic decorative element.

Fig. 11 is a plan view thereof.

Fig. 12 is a sectional view like that of Fig. 8 but showing another modification.

Fig. 13 is a rear plan view of a modified plastic decorative element according to Fig. 12.

The advantages of the invention as here outlined are best realized when all of its features and instrumentalities are combined, but, useful em-

bodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 15 denotes a handbag embodying the invention. The same may comprise side walls 16 and a bottom wall 17 comprising plastic decorative elements 18 interlaced in one or more directions, as shown for example, in my copending patent applications Serial Nos. 553,680 and 554,493. At the top is an opening closed by a slide fastener 19 or other suitable means.

At the ends of the handbag are provided gussets 20 of a pliable material such as leather, textile or plastic. These gussets are provided along their marginal portions with perforations 21 through which pass the corresponding horizontal tapes or lacing 22. The easiest way of assembling the side walls is to thread each horizontal tape through the holes in the flanges or sides 23 of the box-like elements 18 and form each tape into a loop knotted at 24 at the rear of the side wall. The vertical tapes 25 may be similarly arranged and knotted or secured at their upper and lower ends to upper and lower portions of the lining. In either case, the object is to maintain some tension on the tapes 22, 25 to hold the plastic decorative elements snugly together. In this instance, the horizontal tapes or loops engage the gussets 20 in holes 21 to thus secure the gussets at the sides as well as at the bottom of the handbag. Thus the outer wall structure is provided into which a lining may be dropped and connected to upper portions of the lacing in a conventional manner (not shown). The gussets are adapted to infold along a center line 26 so that the mouth of the bag being contracted when closed, and the gussets expanding on opening the bag. Any desired number of rows of plastic decorative elements may be provided at the bottom to make the handbag of any required width.

The holes 21 are unfinished and hence become ragged, and in the case of textile, unraveling may result. Also the gussets 20 form a peculiar unflattering contrast with the decorated plastic side walls. Accordingly, I provide special plastic decorative elements 27 along the bottom and side edges of each gusset, similar to those at 18 and mounted in like manner except that these elements 27 are each provided with an extension 28 adapted to overlie the holes 21. As shown in Figs. 5 and 6, the extension 28 is connected to the main body of element 27 by a spacing wall portion 29 which may be thickened for strength. At this portion 29, the extension 28 may be as long at 28a as the adjacent side wall 30 of the element 27, and connected thereto by wall portions 28b. The extension is spaced from the adjacent side wall 30 through the hole whereof the tape 22 is threaded sufficiently to permit the threading. To permit easy molding, the extension 28 is parallel to the wall 30, and it extends sufficiently beyond the latter to amply conceal the hole 21. These extensions 28 are smaller than the walls 30, and may be of ornamental tab like form as shown in Fig. 4 so that they clear each other at the corners, and so that they are vertically spaced from each other to permit the side walls of the handbag to flex or bulge out-

wardly without obstruction. This arrangement also facilitates the threading of the tape 22 outwardly through the flange 30 past the extension 28, after which the tape is passed through the hole 21 and knotted at 24. If desired this can be done before any of the tapes is knotted, the gusset being loose for easy access to its holes, and then all the tapes threaded through the gusset may be pulled up snugly and knotted. Eventually a stiffener member or board 31 affixed to the lining 32 or otherwise mounted may be inserted into the bag body to bear against the gusset 20 for pressing the edge portions of the gusset outward into alignment with the walls 30 or even against the extensions 28. At any rate, the gusset cannot be pushed outward at its edge portions beyond these extensions.

In Figs. 7 to 11 is shown a modification of the invention wherein the elements 35 are substituted for those at 27. In this case, the extension 36 is formed as a part of the side flange 30 of element 27, but may be thickened for strength, this extension having otherwise the same shape as the parts shown at 28 and 28a. However, the extension 36 is formed with spaced openings at 37, 38 in alignment with each other, through which the horizontal tape 39 is successively threaded to form the knotted loop above referred to. This tape 39 may be looped under itself at 40 closely adjacent to the gusset 41 to retain the latter against the extension 36, and the marginal portion of the gusset may be folded or curled at 42 for increased bulk and reliable engagement with the tape 39 holding it against the extension.

The elements 35 are threaded much more easily and quickly because their openings are fully accessible, and it is easier to pull up and knot each tape 39 as soon as it has been threaded in place. Also the hole 38 affords a secure anchorage which will avoid distortion of the adjacent part of the gusset by the tension of the tape, and the latter can extend laterally at an acute angle to snugly engage around the marginal portion of the gusset. Hence the stiffener 31 may be omitted. In other respects, the remarks addressed to the elements 27 may apply here.

Figs. 10 and 11 show an element 42 like that at 35 but modified for added ornamentation, and to protect the exposed parts of the tapes from rubbing and other wear. Therefore, the ribs 43 extend along the extension 44 and are adapted to receive therebetween and to thus protect the parts of the horizontal tapes exposed as at 45. These ribs are shaped so that the elements 42 can be easily pulled out of a simple mold, but they may be of varied decorative appearance.

Another advantage of the element 42 is that the main part of the extension may be made quite thin so that the holes 46, 47 corresponding to those at 37, 38 can be punched out, as these holes are difficult to mold. Hence the ribs act as a reinforcement and may extend partly along the front wall of the element. Such reinforcement is important since the extensions 44 might otherwise be broken.

In Figs. 12 and 13 is shown another modification wherein the plastic decorative elements 50 serve to hold the gussets 51 at least partially bent inward about their central fold line and prevent the gussets from being pushed outward by the contents of the bag. This is always a problem and is sometimes overcome by a central partition connected to the gussets, but such partition adds substantially to the cost of manufac-

ture. In this instance, the elements 50 are substituted for those at 27 and 35, comprising extensions 52 extending angularly inward from a side wall or flange 53. In other respects the extensions 52 may be like those at 36 or may be ribbed as at 43, and they are beveled off at their ends as at 51a. Preferably a stiff element or cardboard 54 is used to press a loop portion 55 of a horizontal tape 56 against the extension 52 to assist in angularly holding the gusset 51 at the angle of the extension 52. A lining 57 extends along the side walls of the bag, and at 58 along the gussets thereof.

The invention illustrates a continuous tape loop holding tightly a horizontal row of decorative elements and lacing through a pliable expansible end gusset for strongly securing the latter.

I claim:

1. A handbag having flexible side walls each having horizontal rows of decorative elements, horizontal lacing interconnecting the elements, including loop members for all the elements of each row, and end gussets connected to the loop members, the elements adjacent to the gussets having extensions overlying and concealing the gussets at the connections, the extensions being at an angle to the side walls, said extensions being tapered to permit the side walls to flex.

2. A handbag having side walls each having horizontal rows of decorative elements, lacing interconnecting the elements, including lacing members for each row, and end gussets connected to the lacing members, the elements that are adjacent to the gussets having extensions each of which extends beyond the main body of the element and overlies and conceals the connection between the gusset and the lacing member.

3. A handbag having side walls each having horizontal rows of decorative elements, lacing interconnecting the elements, including a lacing member for each row, and end gussets connected to the lacing member, each gusset having a hole for each lacing member and each adjacent element having a first hole and an extension having a second hole, the lacing members passing through both holes of each adjacent element and through an adjacent hole in the gusset, the extension being at an angle to the main body of its element and overlying the portion of the gusset at the hole of the latter.

4. A handbag having side walls of decorative interlaced elements, end gussets, and portions rigidly connected to those elements that are adjacent to the gussets, said portions being at an oblique inward angle to the main bodies of their elements to bear against the gussets and to thus deflect the gussets inwardly.

5. A handbag having side walls having horizontal rows of decorative elements, the main body portions of the elements lying in the planes of their respective side walls, those elements lying along the ends of the walls having extensions projecting toward each other beyond their body portions, and gussets which said extensions partially overlie permitting the gussets to expand and contract, and horizontal lacing interconnecting the elements and the gussets, the extensions having openings for loop portions of the lacing.

6. A handbag having side walls having horizontal rows of decorative elements, the main body portions of the elements lying in the planes of their respective side walls, those elements lying along the ends of the walls having extensions projecting toward each other beyond their body portions, and gussets which said extensions partially overlie permitting the gussets to expand and contract, and horizontal lacing interconnecting the elements and the gussets, the extensions having openings for loop portions of the lacing, the extensions having reinforcing ribs thereon on the outside thereof along which the loop portions extend.

7. A handbag having side walls having horizontal rows of decorative elements, the main body portions of the elements lying in the planes of their respective side walls, those elements lying along the ends of the walls having extensions projecting toward each other beyond their body portions, and gussets which said extensions partially overlie permitting the gussets to expand and contract, said lacing being horizontal and interconnecting the elements and the gussets along spaced lines lying generally centrally of rows formed by the elements, said extensions constituting tabs spaced from each other and overlying the gussets in central relation to the lacing.

8. A handbag having side walls having horizontal rows of decorative elements, flexible means horizontally mounting the rows of elements, and end gussets connected to the flexible means at the ends of the rows, the elements having adjacent to the gussets extensions each of which extends beyond the main body of its element and overlies and conceals the connection between the gusset and the flexible means at the different rows.

9. A handbag according to claim 8 wherein the said extensions are at an oblique inward angle to the main bodies of the elements to bear inward on the gussets for deflecting the latter inward.

JANET SAMUELSON.
